UNITED STATES PATENT OFFICE.

LEONARD B. BUCHANAN, OF WOBURN, MASSACHUSETTS.

ELECTRIC FUSE OR CUT-OUT.

No. 851,157.

Specification of Letters Patent.

Patented April 28, 1907.

Application filed May 28, 1906. Serial No. 319,077.

To all whom it may concern:

Be it known that I, LEONARD B. BUCHANAN, of Woburn, county of Middlesex, State of Massachusetts, have invented an improvement in Electric Fuses or Cut-Outs, of which the following description, in connection with the accompanying drawings, is a specification, like characters on the drawings representing like parts.

10 This invention relates to electric fuses or cut-outs having fuse-indicators, and has for its object to provide improved means for operating the fuse-indicator when the fuse-wire ruptures:

15 Figure 1 shows in side elevation an electric fuse or cut-out embodying this invention. Fig. 2 is an enlarged sectional detail showing one end of the fuse or cut-out, the fuse-indicator and means for operating it. Fig. 3 is a sectional detail, similar to Fig. 2, showing the fuse-wire as ruptured and the fuse-indicator in the act of being ejected. Fig. 4 is a sectional detail of the support for the actuating-spring for the fuse-indicator. Fig. 5 is a sec-
25 tional detail showing modified means for connecting the actuating spring for the fuse-indicator with the fuse-wire. Fig. 6 is a detail of the actuating spring shown in Fig. 5.

20 *a represents the shell or case of the electric fuse or cut-out, which is herein shown as cylindrical, but it may be of any other desirable form. b, b represent the end caps of said shell or case, c the main fuse-wire, and d the shunt fuse-wire, both of which are contained 35 in said shell or case, and are herein shown as connected to the end caps. This type or form of electric fuse or cut-out is herein shown merely for the sake of illustrating my invention, as I desire it to be understood that 40 my invention may be applied to other types or forms of inclosed filled electric fuses or cut-outs.

45 The fuse-indicator herein shown consists of a small circular disk e, of leather or other material, placed in an aperture formed in the wall of the shell or case a, at any desirable part thereof, and for the purpose of indicating when the fuse-wire ruptures, said disk is ejected.

50 As my invention particularly resides in the means for operating the fuse-indicator, I do not desire to limit it to the construction or form of the fuse-indicator which is employed.

The form herein shown, however, is simple, cheap to manufacture and easily discernible. 55

A spring f is employed as the actuator for the fuse-indicator, and this spring is located beneath the fuse-indicator e, and is herein shown as made helical, and in Figs. 2, 3 and 4, as having at its upper or outer end an eye 60 f' through which the fuse-wire d passes, and in Figs. 5 and 6 as having its upper or outer end extended down through the center of the spring and connected with the fuse-wire c. The spring may be connected with either the 65 shunt fuse-wire or main fuse-wire. A support is provided for the spring f, which, as shown in Figs. 2, 3 and 4, consists of a cap g adapted to be placed in the aperture in the shell or case, the flanged head or end of which 70 is located upon the inside of the shell or case. The spring is contained in said cap and is supported upon the inside of the head or end thereof. The cap is made shallow, its length approximately equalling the thickness of the 75 wall of the shell or case, and the fuse-indicator e is so proportioned that the actuating-spring f, when compressed, will occupy a position directly beneath it, so that when said spring is released and permitted to resume 80 its normal condition the indicator e will be engaged and ejected. As the cap g herein shown approximately equals the thickness of the 85 wall of the shell or case, the disk e will be made to snugly fit it so as to be confined or held in place by it, that is to say, by frictional engagement one with the other.

As shown in Figs. 2, 3 and 4, the walls of the cap g are perforated to provide for the passage through it diametrically of the fuse-wire, and the actuating-spring, which is contained in the cap is compressed and the fuse-wire passes through the eye which is formed on said spring, and thus acts to hold said spring compressed. When the fuse-wire 95 ruptures the spring will be released and will immediately resume its normal condition, and the fuse-indicator will be ejected. This construction is preferable for small fuses. For large fuses a plate h is placed against the 100 inside of the shell or case, over the aperture, which serves as a support for the spring, and said plate has a small hole through it through which the downwardly extended end of the actuating spring passes, and said end is connected to the fuse-wire, so that the actuating- 105

spring will be held compressed by said fuse-wire. When the fuse-wire ruptures the spring will be released and permitted to resume its normal condition and the fuse-indicator will be ejected, as before described.

Having thus described my invention, what I claim as new and desire to secure by Letters Patent is:—

1. In an electric fuse or cut-out, a shell or case containing a fuse-wire, a fuse-indicator, and an actuating-spring for said indicator which is located beneath but disconnected from the indicator, and which is connected with and held compressed by said fuse-wire, substantially as described.
2. In an electric fuse or cut-out, a shell or case containing a fuse-wire, a fuse-indicator, means for holding it confined, and an actuating-spring for said indicator which is located beneath it, and which is formed with an eye through which the fuse-wire passes, whereby said spring is connected with and held compressed by the fuse-wire, substantially as described.
3. In an electric fuse or cut-out, a shell or case containing a fuse-wire and having an aperture, a removable disk contained in said aperture, and a spring located beneath said disk but disconnected therefrom which is normally held compressed by the fuse-wire and which, when released by the fuse-wire rupturing, operates to eject the disk, substantially as described.
4. In an electric fuse or cut-out, a shell or case containing a fuse-wire, a fuse-indicator, an actuating-spring for said indicator which is located beneath it and which is connected with and held compressed by said fuse-wire, and a cap containing said spring through which the fuse-wire passes, substantially as described.
5. In an electric fuse or cut-out, a shell or case having an aperture, a fuse-wire contained in said shell or case, a cap placed in said aperture, an indicating-disk placed in said cap, a spring for ejecting said disk also placed in said cap beneath the disk, which is connected with and held compressed by the fuse-wire, substantially as described.
6. In an electric fuse or cut-out, a shell or case containing a fuse-wire, a helical spring connected with said fuse-wire and normally held compressed by it, and a fuse-indicator located adjacent said spring, which is engaged and operated by said spring when the latter is released, and means, independent of the spring for holding the indicator confined, substantially as described.
7. In an electric fuse or cut-out, a shell or case containing a fuse-wire, a helical spring having an eye at one end through which said fuse-wire passes, and a support for said spring upon which it is held compressed by said fuse-wire, substantially as described.
8. In an electric fuse or cut-out, a shell or case containing a fuse-wire, a helical spring connected with said fuse-wire, and a support for said spring upon which it is normally held compressed by said fuse-wire, a fuse-indicator adapted to be operated by said spring when released, and means for holding said indicator confined while the spring is compressed, substantially as described.
9. In an electric fuse or cut-out, a shell or case having an aperture and containing a fuse-wire, a helical spring contained in said aperture which is connected with said fuse-wire, and a support for said spring upon which it is normally held compressed by said fuse-wire, a fuse-indicator adapted to be operated by said spring when released, and means for holding said indicator confined while the spring is compressed, substantially as described.
10. In an electric fuse or cut-out, a shell or case containing a fuse-wire, a helical spring having an eye at one end through which said fuse-wire passes, and a support for said spring upon which it is held compressed by said fuse-wire, and a fuse indicator adapted to be operated by said spring when released, substantially as described.
11. In an electric fuse or cut out, a shell or case having an aperture, a fuse-wire contained in said shell or case, a cap placed in said aperture through which the fuse-wire passes, an indicating disk placed in said cap, a spring for ejecting said disk also placed in said cap beneath the disk, which is connected with and held compressed by the fuse-wire, substantially as described.
12. In an electric fuse or cut-out, a shell or case having an aperture, a fuse-wire contained in said shell or case, a flanged cap placed in said aperture through which the fuse-wire passes, an indicating-disk placed in said cap, a helical spring for ejecting said disk also placed in said cap beneath the disk, which is connected with and held compressed by the fuse wire, substantially as described.
13. In an electric fuse or cut-out, a shell or case containing a main fuse wire and an auxiliary fuse wire, a fuse indicator and an actuating spring for said indicator which is located beneath but disconnected from the indicator and which is held compressed by said auxiliary fuse wire, substantially as described.
14. In an electric fuse or cut-out, a shell or case containing a main fuse wire and an auxiliary fuse wire, a fuse indicator, an actuating spring for said indicator which is held confined by said auxiliary fuse wire, and independent means for holding the indicator confined while its actuating spring is held confined, substantially as described.
15. In an electric fuse or cut-out, a shell or case containing a main fuse wire, and an aux-

iliary fuse wire, a fuse indicator and helical spring connected with the auxiliary fuse wire and normally held compressed by it, a fuse indicator located adjacent said spring which is engaged and operated by said spring when the latter is released, and independent means for holding said indicator confined while said actuating spring is held compressed, substantially as described.

16. In an electric fuse or cut-out, a shell or case having an aperture and containing a main fuse wire and an auxiliary fuse wire, a fuse indicator, an actuating spring for said indicator normally held compressed by said auxiliary fuse wire, and independent means for holding said indicator confined in said aperture while its actuating spring is held compressed, substantially as described.

17. In an electric fuse or cut-out, a shell or case having an aperture and containing a main fuse wire and an auxiliary fuse wire, an indicating disk adapted to be ejected from said aperture, an actuating spring for said disk normally held compressed by said auxiliary fuse wire, and independent means for holding said disk confined in the aperture while its actuating spring is held compressed, substantially as described.

In testimony whereof, I have signed my name to this specification, in the presence of two subscribing witnesses.
